S. H. FURRY.
BRIDGE APPROACH.
APPLICATION FILED OCT. 8, 1917.

1,300,949.

Patented Apr. 15, 1919.

UNITED STATES PATENT OFFICE.

SAMUEL H. FURRY, OF LANCASTER, OHIO.

BRIDGE-APPROACH.

1,300,949.

Specification of Letters Patent. Patented Apr. 15, 1919.

Application filed October 8, 1917. Serial No. 195,472.

To all whom it may concern:

Be it known that I, SAMUEL H. FURRY, a citizen of the United States, residing at Lancaster, in the county of Fairfield and 5 State of Ohio, have invented certain new and useful Improvements in Improved Bridge-Approaches, of which the following is a specification.

This invention relates to improvements in 10 paving and, it is the principal object of the invention to provide a novel form of approach for use in connection with bridges whereby to eliminate the jolting of a vehicle moving thereover and also reducing the pull 15 or draft to minimum by reason of the gradual and even grade afforded thereby.

Another and equally important object of 20 the invention is to provide a bridge approach which is of such construction as will render 25 the same exceedingly strong and durable; hence, preventing excessive wearing thereof and the "washing out" of portions of the same by reason of the flow of water thereover and also, affording an effectual hold for 30 the feet of draft animals passing thereover.

The invention consists, furthermore, in the 35 novel combinations of parts of the approach, as well as in the details of construction of the same, all of which will be more fully 40 described in the following specification, and then finally embodied in the clauses of the claim which are appended to this specification and which form an essential part of the same.

35 In the drawings:

Figure 1 is a top plan of the improved approach, a portion of which is broken away.

Fig. 2 is a similar view of a slightly modified form of approach,

40 Fig. 3 is a longitudinal section taken on the line 3—3 of Fig. 1, and

Fig. 4 is a similar view taken on the line 4—4 of Fig. 2.

Having more particular reference to the 45 drawings, in connection with which like reference characters will designate corresponding parts throughout the several views, 1 designates a portion of the bridge to which the improved approach is applied and 2 the 50 roadway communicating therewith, which roadway, as will be noted, is formed with a "rise" 3, the purpose of which will be presently apparent.

A portion of the "rise" 3 is removed and 55 is filled with a plastic, preferably concrete,

bed 4, the lower end of which is curved or off-set as at 5 to provide a drain or gutter extending transversely of the same and into which gravel or loose rock 6 is placed. In this connection, it will be noted that a portion of the exposed surface of the bed is corrugated at 7 and is arranged flush with the surface of the adjoining portion of the "rise" 3, thus, enabling the vehicle to move easily thereover; the corrugations 7 serving to provide an effectual foot hold for draft animals and as a non-skid surface for the wheels of the vehicles passing thereover.

60 Embedded in the bed 4 of the approach 6 is a corrugated metal sheet 8 formed with a plurality of perforations generally indicated by the numeral 9, whereby to permit passage of the concrete therethrough and resultant tying or binding of the same therein. The lower end of the reinforce is bent upon itself 65 as at 10 to conform in shape to the curved portion 5, while the upper or remaining end thereof is extended into the plastic material from which the bridge flooring is constructed, as indicated by the reference numeral 11. 70

In this way, undue movement of the reinforcement with relation to the bridge flooring will be positively prevented and further, disconnection of the same from the bridge and the resultant "rut" will be prevented.

75 In the Figs. 2 and 4, I have illustrated a slightly modified form of approach, and in this embodiment, the plastic approach bed 4' has the corrugated exposed surface thereof covered by a corrugated metal sheet 12, 80 the lower end of which is bent downwardly at 13 and engaged therein, while the upper end is formed with a laterally extending plane lip 14 adapted to be movably engaged in a pocket or seat 15 formed on the adjacent portion of the bridge 1', which bridge, in this instance, has a metal or other suitable form of non-plastic flooring. By reason of the mode of engagement of the reinforcement 12 with the bridge, it will be readily understood that the expansion and contraction of the approach and the bridge are provided for.

85 It may be here noted, that the corrugations formed in the exposed surfaces of the approach bed 4 indicated by the numeral 7, and the corrugations formed in the reinforcement 12 are substantially V-shaped and as a consequence, insure the proper drainage 90 of water therefrom.

I desire to have it understood, that the utility of the invention is not limited to the form thereof herein shown, but if desired, can be adapted for use in connection with 5 culverts, road grades, road crossings and steps.

As hereinbefore indicated, I do not wish to be understood as confining the invention to the particular embodiments chosen for 10 illustration herein, nor to the exact construction and arrangement and adaption of parts shown and described, but I reserve the right to make any changes and alterations that fairly fall within the spirit and scope of the 15 invention.

I claim:

1. In combination with vertically disaligned communicating ways, an approach arranged between the same and adjoining flush therewith, and reinforcing means engaged with 20 said approach and connected to one of said ways.
2. In combination with vertically disaligned communicating ways, an approach arranged therebetween and adjoining flush therewith, the lower end of said approach being formed with a transverse drain, and re- 25

inforcing means in said approach engaged with one of said ways.

3. In combination with vertically disaligned communicating ways, an approach arranged between the same and adjoining flush therewith, the exposed surface of said approach being corrugated, and a transverse drain arranged in the lower end of said approach. 30 35

4. In combination with vertically disaligned communicating ways, an approach arranged therebetween and adjoining flush therewith, a corrugated reinforce engaged with the approach, the lower end of said approach being formed with a transversely disposed drain, and means for effecting connection between one end of said reinforce 40 and one of the ways. 45

5. In combination with vertically disaligned communicating ways, an approach arranged therebetween and adjoining flush therewith, a corrugated reinforcing element 50 embedded in said approach having one end extended into engagement with one of the ways, the lower end of said approach being formed with a transversely disposed drain.

SAMUEL H. FURRY.
